R. S. MACEWAN,
REAMER FRAME,
APPLICATION FILED NOV. 26, 1919.

1,339,118.

Patented May 4, 1920.

Inventor

Robert S. MacEwan

UNITED STATES PATENT OFFICE.

ROBERT S. MACEWAN, OF TROY, NEW YORK.

REAMER-FRAME.

1,339,118.

Specification of Letters Patent.

Patented May 4, 1920.

Application filed November 26, 1919. Serial No. 340,961.

(FILED UNDER THE ACT OF MARCH 3, 1883, 22 STAT. L., 625.)

To all whom it may concern:

Be it known that I, ROBERT S. MACEWAN, a citizen of the United States, and a resident of Troy, county of Rensselaer, State of 5 New York, have invented an Improvement in Reamer-Frames, of which the following is a specification.

The invention described herein may be used by the Government, or any of its officers 10 or employees in prosecution of work for the Government, or by any other person in the United States, without payment of any royalty thereon.

This invention relates to improvements 15 in reamer frames and is particularly adapted for holding reamers used in boring guns, but is also of general application where accuracy and alinement is necessary such as in the boring and reaming of engine cylinders.

20 In placing a new liner in guns, the bore of the gun is reamed to a taper which must be true and uniform. Previous to this operation, however, the gun is bored so as to form a series of steps of cylinders having

25 different diameters, which increase in diameter toward the breech end. Each step is usually about 30 inches long. These cylindrical portions are bored by means of a boring bar which is well supported at each end 30 and intermediately in order that the axes of the different cylinders may be in alinement.

In using reamers, unless the body of the 35 reamer is supported and guided, it is difficult to hold it exactly in line with the bored hole and my invention has also in view a means for guiding the reamer which will then produce accurate work. This is accomplished by a reamer frame of simple 40 construction which can be readily applied to position.

In the following description, reference is made to the accompanying drawings in which:—

45 Figure 1 is an end elevation of my reamer frame with the reamer body shown in section; and

Fig. 2 is a section of Fig. 1 on the lines 2—2.

50 The numeral 1 designates the body of the reamer, which projects in front of the cutting edges and will be herein termed a pilot. To opposite parallel sides of the pilot 1, are applied the two segments 2, 3 of a holding frame. This frame may be of any suit-

able material but is preferably cast iron or steel and is machined to present finished surfaces to the sides of the pilot 1. The frame parts 2, 3 each comprise a rim portion, a hub portion 10 and spokes 11 which 60 extend radially from the hub portion and support the rim at equally spaced intervals. The spokes 11 are reduced in weight by means of the open spaces formed therein as shown in Fig. 2.

65 The frame parts 2, 3 are formed with a plurality of lugs 4 projecting from the rim portion, which are machined to form shoulders 5 and 6 at right angles to each other. In the recess formed by the shoulders 5 and 70 6, wood or fiber blocks 7 are inserted. These wood blocks are secured to the frames 2 and 3 by means of screw bolts 8. A lug 4 projects from the rim at each spoke 11 so that the lugs are uniformly spaced about the 75 circumference. The end spokes of each segment extend from the hub portion 10 in opposite directions so as to form a chord for the segment.

80 The two segments of the frame are secured to the pilot 1 by means of bolts 9 which pass through the end spokes of each segment. When mounted on the pilot 1, the segments conform to the circumference of a complete circle. The wood blocks 7 85 are cut so that when assembled they conform to the circumference of a circle of the desired diameter. Owing to the different diameters of the steps previously machined in boring the gun, it is necessary to have a 90 plurality of sets of blocks 7 to fit these various diameters. It can be seen that these blocks can be readily changed by simply unscrewing the bolts that secure the blocks in position and replacing them with new 95 blocks of the desired dimensions.

95 In reaming the bore of the gun, the blocks 7 are selected to give a diameter that will snugly fit the next cylindrical step and thereby act as a pilot bushing in front of the 100 reamer and assure that the reamer will cut a true taper without variation. It will be understood that this invention can also be applied in reaming a simple cylinder of uniform diameter since it will act as a pilot 105 in starting the reamer, and also guide it during operation.

110 This is important in view of the fact that it is very difficult to locate a reamer exactly in line with a bored hole because of slight

variations in the indexing of the turret, or errors resulting from the guide-ways or other important parts of the machine. By having a pilot bushing of the type herein described, in front of the reamer, such errors are effectually eliminated.

Having described my invention, what I claim as new and desire to secure by Letters Patent, is:—

- 10 1. A reamer frame comprising a plurality of parts adapted to support guide blocks, said parts, when assembled to the reamer frame, conforming to the circumference of a circle.
- 15 2. A reamer frame comprising segmental parts having projecting lugs, means for securing guide blocks in said lugs, and means for securing said segmental parts to the reamer body.
- 20 3. A reamer frame comprising segmental sections adapted to be secured to the reamer

body, lugs projecting from said segmental parts and guide blocks secured in said lugs whereby said reamer body is guided and supported in front of the reamer blades.

25 4. A reamer frame comprising segmental sections adapted to be secured to a reamer body, a plurality of lugs projecting from said segmental sections, each lug having a shoulder formed therein, a guide block abutting said shoulder and means for securing the blocks to said lug.

30 5. A reamer frame comprising segmental sections having a hub portion, a rim portion, spokes extending radially from said hub portion for supporting said rim, a plurality of lugs projecting from said rim portion, wood blocks detachably secured to said lugs and means for securing said sections to the body of a reamer.

35 ROBERT S. MACEWAN.
